UNITED STATES PATENT OFFICE.

CHARLES A. CADWELL, OF CLEVELAND, OHIO, ASSIGNOR TO THE ELECTRIC RAILWAY IMPROVEMENT COMPANY, OF CLEVELAND, OHIO, A CORPORATION OF OHIO.

ELECTRIC FURNACE.

Application filed November 8, 1922. Serial No. 599,641.

To all whom it may concern:

Be it known that I, CHARLES A. CADWELL, a citizen of the United States, and a resident of Cleveland, county of Cuyahoga, and State of Ohio, have invented a new and useful Improvement in Electric Furnaces, of which the following is a specification, the principle of the invention being herein explained and the best mode in which I have contemplated applying that principle, so as to distinguish it from other inventions.

The present improvements relate more particularly to an electric furnace of the oven type wherein a resistor of granular material is employed, in conjunction with a plurality of electrodes so disposed relatively to said resistor that arcs are formed therebetween with resultant additional heating effect.

Electric ovens for ordinary purposes are heated by passing an electric current through metallic resistance paths, such as cast iron grids or various kinds of resistance wire. Such metallic resistance material constitutes in itself substantially all of the electrical equipment needed for any design of oven within the temperature range of such material, no auxiliary apparatus being required for control. However, the maximum temperature of such an oven cannot be greater than that which may be derived by radiation from the metallic resistor at a safe working temperature for the latter; although the maximum temperature thus derived can be very nearly equal to such limiting temperature of the resistor, this being made possible by the uniformity of temperature of every part of the heating element and the easy distribution of the element itself.

Where in order to provide a higher temperature than can be obtained in an oven heated by such a metallic resistor, an electric arc or a granular resistor is employed, relatively elaborate and costly electrical equipment has heretofore been necessary for the operation and control of the furnace. Especially does such a furnace lack the uniform distribution of heat energy characteristic of the metallic resistor ovens, being dependent rather upon radiation from sources of extremely high heat intensity such as an arc of large current capacity or the resistance of a large resistor body. In other words, where

such a heating element is used, it is necessary to transform electric current from the ordinary transmission lines by means of massive transformers and conductors into current of very large amperage and lower voltage. Such an installation is necessarily costly in itself and requires costly control apparatus.

One object of the present invention, accordingly, is to provide an oven or furnace wherein the temperature obtainable may far exceed the safe limit for metallic resistor ovens and yet in which it is possible to realize the simplicity of construction, ease of control and small cost of the latter. A further object is to render it possible to utilize current taken directly from ordinary transmission lines without any transformation whatever and with no more control apparatus than is used in the metallic resistor type of oven.

The need for such an oven has long been felt for purposes that require not only a higher temperature than that obtainable from the aforesaid metallic resistor type of oven, but also require a more accurate control of the rate and uniformity of heating and of the gases in the heating chamber, than can be obtained from ordinary fuel fired furnaces.

For example, in the firing of fine pottery, a slow drying heat is required at the start and at all times the ware must be protected against sudden changes of temperature which may occur in a fuel fired furnace.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a central vertical section of a furnace embodying my present improvements; Fig. 2 is a top plan view of the furnace proper with the cover removed and other accessory parts sectioned on the plane indicated by the line 2—2, Fig. 1; Fig. 3 is a transverse horizontal section of such fur-

nace, the plane of the section being indicated by the line 3—3, Fig. 1; Fig. 4 is partly a plan view and partly a transverse horizontal section of certain auxiliary parts whereby the electrodes are adjustably supported in the furnace, the plane of such section being indicated by the line 4—4, Fig. 1; Fig. 5 is a more or less diagrammatic representation of the wiring connections to the several electrodes; Fig. 6 is a sectional view of a detail of the apparatus accessory to the furnace proper; the section being taken on the same plane as is Fig. 1 but on a larger scale; and Fig. 7 is a perspective view of another detail of such apparatus.

The oven or furnace chamber 1, in the illustrative form shown in the drawings, is primarily designed for firing pottery or for heating other articles of a similar character and requiring similar treatment. Such chamber accordingly conveniently takes the form of an approximately circular well sunk practically flush with the surface of the surrounding floor. A refractory wall 2 of fire-brick or like material, which may be backed with heat insulating material, forms the outer confines of the chamber 1, while an inner cylinder 3 forms the lateral wall of the oven chamber proper. Instead of the well being circular and such wall 3 of cylindrical form, both may take the form of a regular polygon in cross-section. Such inner wall 3 is preferably of carborundum or of equivalent refractory material having a high heat conductivity and an electrical resistivity that classes it as no more than a secondary conductor. The purpose of this wall is that of a heat diffusing and distributing medium, as well as that of a container for an oven product that requires a specified atmosphere; and where such oven product is a melted metal, such inner wall may take the form of a crucible, i. e., the cylinder will be closed at the bottom and so rendered capable of being removed with the charge.

In any case such inner chamber wall 3 rests on a layer 4 of granular carbon or equivalent material that forms the floor of the well, and a supplemental layer 5 of the same or similar material is placed in the bottom of the annular space between walls 2 and 3. Embedded in such layer 4 is a series of resistor elements 6 (best shown in Figs. 1 and 3), which preferably consist of short pieces of cylindrical carbon rod spaced at short intervals and laid transversely of such layer, i. e., in a general radial direction with respect to the center of the furnace chamber. The general construction of the resistor forms the subject-matter of my co-pending application filed April 29, 1920, Serial No. 377,430, where such construction is broadly claimed.

Within the annular resistor space between

walls 2 and 3 are suspended a number of carbon electrodes 7 at regular intervals. In the case of a chamber having a polygonal cross-section, such electrodes will be located at the splices of the polygon and on account of the general use of 3-phase electric current, the number of such electrodes will usually be three for the smaller sizes of oven and some multiple of three for the larger sizes, observing only that any electrode on phase 1, for example, should be adjacent to phase 2 on one side and phase 3 on the other. Accordingly current flowing through adjacent electrodes and the portion of the resistor element consisting of the layer 5 and embedded carbon rods 6 lying between the lower ends of such electrodes, will encounter the resistance of such element and also that of two arcs. Aside from adding to the resistance of the oven, these arcs also furnish a basis of control from an automatic variation of length, as will be presently described.

The voltage of the power line determines the length of the portion of the resistor element between adjacent electrodes and hence determines the number of the latter that can be used in a given sized unit. As a means for increasing the length of the resistor element and therefore of the number of electrodes, without increasing the diameter of the annular resistor chamber, I may place beneath each electrode, as shown in Figs. 1 and 3, a cylindrical tile 8 of carborundum or equivalent heat resisting material and filled with granular carbon 9, such tile with its filling resting upon the resistor element below and being placed with its axis coincident with that of the electrode above. In this case the electrode will arc to the top of such cylindrical tile into the granular filling 9 and the radiating surface of the resistor element is thereby not only increased, but better heat distribution is secured due to the vertical disposition of such added portion of the resistor.

Where the inner wall 3 of the oven is designed to remain permanently in place, the annular resistor space or chamber between said wall and outer wall 2 will be closed at its upper end by blocks 10 of refractory material, the inner edges of which project a short distance beyond such inner wall so as to leave an opening through which access may be had to the interior of the oven, as shown in Fig. 2. This opening is then in turn adapted to be closed by means of a cover 11, of similar refractory material, that may be lifted or otherwise removed when access to the oven is desired. Where the inner wall 3 is in the form of a crucible, which requires to be lifted out of the furnace, the blocks 10 will, of course, have to be supported with their inner edges clear of the upper end of such wall. It may also

be found desirable to provide a second or false bottom (not shown) within said wall 3 which may be raised and lowered with a charge, without disturbing the disposal of the apparatus located over the oven from which the electrodes 7 are suspended.

Certain of the blocks 10 are provided with circular openings 12 fitted with short upwardly extending iron tubes 13 through which the electrodes 7 are freely movable in a vertical direction, perforated plates 14 of asbestos or the like, fitting more tightly about the electrodes, serving to close the upper ends of such tubes 13.

15 The apparatus or mechanism from which the electrodes are thus suspended comprises a frame in the form of an open cage 15 which serves at the same time as a base for the distribution of current to said electrodes and as a mounting for the control device with which each electrode is provided. Said cage is itself suspended from a point overhead so as to be vertically adjustable as a whole, a convenient means for such support and adjustment comprising a cable 16, one end of which passes over a pulley 17 and is attached to said cage, while the other end is connected by means of a turn-buckle 18, or like device, to a fixed point of support 19. By the foregoing means, the cage with the electrodes suspended therefrom may be raised or lowered so as to accurately vary the arc length of the electrodes as a unit. The current for the electrodes is received at the upper end of the cage, the three incoming conductors 20 where the current is 3-phase, as hereinbefore assumed, being connected to binding posts 21 corresponding in number to the number of electrodes, as shown in Fig. 5. From the distributing point at the top of the cage provided by such binding posts, lengths of bare flexible conductors 22 of nichrome, or other non-corrosive or non-oxidizing metal, capable of operating without injury at a red heat, are stretched vertically to corresponding posts 23 at the lower end of the cage, a suitable length for such conductors being three feet in the case of a furnace such as illustrated. It will be understood, of course, that the binding posts 21 and 23 are suitably insulated from the cage so that the current may pass through each such conductor 22 directly to the corresponding electrode through a flexible copper conductor 24 extending from such last-mentioned binding posts to the electrode holder 25. Said holders 25 are provided with upwardly extending rods or stems 26 that are received and adjustably held in tubular members 27, or equivalent clamping devices, and the latter are in turn supported from the cage by means of cords 28 that pass over pulleys 29 mounted in said cage and that have suitable counterweights 30 attached at their inner ends. It will be understood that the holders 25 are, of course, insulated from the supporting means thus provided and it should be further explained that each counterweight 30 slightly overbalances the corresponding electrode and other parts attached to the outer end of its cord 28. The resultant tendency of the weight to raise the electrode is, however, restrained by a horizontally extending cord 31, the inner end of which is attached, through the medium of an insulator 32, to an adjacent point on the corresponding nichrome conductor 22, while the outer end passes around and is attached to the periphery of a pulley 33, which pulley is fixed to the corresponding pulley 29 so that the two pulleys must always rotate together. As clearly shown in Fig. 1, the direction in which each cord 31 thus passes around its corresponding pulley 33 is such as to pull on the conductor 22, to which said cord is attached at its inner end, as on a bow string. The lengthening or shortening of such conductor 22 will accordingly cause a rotation in one direction or the other of the attached pulleys 33 and 29, with the result that the vertical position of the corresponding electrode will be changed. For example, a current flow through any conductor 22, which increases the temperature of such conductor, will, by the same token, increase its length and so allow the counterweight attached to the corresponding electrode to raise the latter. As a result the arc between such electrode and the resistor element will be lengthened until the increased resistance will cause a decrease of current flow in said conductor 22, thereby shortening the latter and restoring the electrode again to its proper relation to the resistor. On the contrary, a drop in the current flow will effect a downward adjustment of the electrode, thereby tending to lower the resistance and re-establish the normal current flow. The control action may be multiplied as desired by varying the length of the nichrome conductor or changing the ratio of the diameters of the pulleys 29 and 33, as will be readily understood.

In operating the oven the electrodes are first brought into contact with the resistor element by lowering the cage as a whole and by adjustment of the clamp devices, including rod 26 and tube 27, whereby the individual electrodes are adjustably supported. Thereupon the current is switched on and the electrodes, due to the lengthening of conductors 22, will immediately rise and start the arcs, following which the arcs are automatically maintained at the proper length by the action of said conductors, as has just been explained. If when the arcs are established and the oven is running steadily it is desired to increase the flow of current and thus increase the rate of heating,

it is necessary only to slightly lower the cage and thus the electrodes as a whole; while to retard the rate of heating, the cage and electrodes will be similarly raised.

5. Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In an electric furnace, the combination 15 of an approximately circular chamber; an annular resistor at one end of said chamber; and a series of electrodes extending into said chamber from the opposite end and approximately parallel with the axis thereof to within arcing range of said resistor.

2. In an electric furnace, the combination 25 of an approximately circular chamber; an annular resistor at one end of said chamber; and a series of electrodes extending into said chamber from the opposite end and approximately parallel with the axis thereof to within arcing range of said resistor, said resistor being constructed so as to provide a path of least resistance for the 30 current in passing from one of said electrodes to the other in a plane spaced from the adjacent end of said chamber.

3. In an electric furnace, the combination 35 of an approximately circular chamber; an annular resistor at one end of said chamber; and a series of electrodes extending into said chamber from the opposite end thereof to within arcing range of said resistor, said resistor consisting of granular carbon and 40 members of greater electrical conductivity embedded therein.

4. In an electric furnace, the combination 45 of an approximately circular chamber; an annular resistor at one end of said chamber; and a series of electrodes extending into said chamber from the opposite end thereof to within arcing range of said resistor, said resistor consisting of granular carbon and a plurality of carbon rods embedded therein 50 and disposed in a radial direction with respect to the axis of said chamber.

5. In an electric furnace, the combination 55 of an approximately circular chamber; an annular resistor at one end of said chamber; and a series of electrodes extending into said chamber from the opposite end thereof to within arcing range of said resistor, said resistor including elements projecting therefrom in line with said electrodes, respectively.

6. In an electric furnace, the combination 65 of an approximately circular chamber; a refractory wall within said chamber spaced from the outer wall thereof; a resistor at one end of said chamber disposed in the

annular space between such walls; and a series of electrodes extending into such space from the opposite end of said chamber to within arcing range of said resistor.

7. In an electric furnace, the combination 70 of an approximately circular chamber; a refractory wall within said chamber spaced from the outer wall thereof; a resistor at one end of said chamber disposed in the annular space between such walls; and a series 75 of electrodes extending into such space from the opposite end of said chamber to within arcing range of said resistor, said resistor being constructed so as to provide a path of least resistance for the current in passing from one of said electrodes to the other in a plane spaced from the adjacent end of said chamber.

8. In an electric furnace, the combination 85 of an approximately circular chamber; a refractory wall within said chamber spaced from the outer wall thereof; a resistor at one end of said chamber disposed in the annular space between such walls; and a series 90 of electrodes extending into such space from the opposite end of said chamber to within arcing range of said resistor, said resistor including elements projecting therefrom in line with said electrodes, respectively.

9. In an electric furnace, the combination 100 of a vertically disposed, approximately circular chamber; a refractory wall within said chamber spaced from the outer wall thereof; a resistor at the bottom of said chamber disposed in the annular space between such walls; and a series of electrodes approximately parallel with the axis of said chamber depending vertically from above into such space to within arcing range of said 105 resistor.

10. In an electric furnace, the combination 110 of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range of said resistor; and means affected by the flow of current to said electrodes adapted automatically to raise and lower the same individually.

11. In an electric furnace, the combination 120 of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range of said resistor; means adapted to raise and lower said electrodes as a unit; and means affected 125

by the flow of current to said electrodes adapted automatically to raise and lower the same individually.

12. In an electric furnace, the combination of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range on said resistor; manually adjustable means for raising and lowering individual electrodes; and means affected by the flow of current to said electrodes adapted automatically to raise and lower the same individually.

13. In an electric furnace, the combination of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range of said resistor; means adapted to raise and lower said electrodes as a unit; manually adjustable means for raising and lowering individual electrodes; and means affected by the flow of current to said electrodes adapted automatically to raise and lower the same individually.

14. In an electric furnace, the combination of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range of said resistor; conductors for supplying current to said electrodes, respectively, said conductors including sections secured to points a predetermined distance apart; and means adapted automatically to raise and lower said electrodes individually, said means being affected by variations in length of the corresponding conductor sections due to changes in current flow therethrough.

15. In an electric furnace, the combination of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range of said resistor; conductors for supplying current to said electrodes, respectively, said conductors including sections secured to points a predetermined distance apart; means connected with individual electrodes tending to raise the same;

and connections between said means and the corresponding conductor sections, whereby variations in length of the latter serve to control said means.

16. In an electric furnace, the combination of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range of said resistor; conductors for supplying current to said electrodes, respectively, said conductors including sections secured to points a predetermined distance apart; a pulley adjacent each such conductor section; a cable connected with the corresponding electrode and passing over such pulley, said cable being counter-weighted so as to tend to raise said electrode; and a cord connecting each pulley with the adjacent conductor section whereby the shortening of the latter tends to lower said electrode.

17. In an electric furnace, the combination of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range of said resistor; conductors for supplying current to said electrodes, respectively, said conductors including sections secured to points a predetermined distance apart; a pulley adjacent each such conductor section; a cable adjustably connected with the corresponding electrode and passing over such pulley, said cable being counter-weighted so as to tend to raise said electrode; and a cord connecting each pulley with the adjacent conductor section whereby the shortening of the latter tends to lower said electrode.

18. In an electric furnace, the combination of a vertically disposed, approximately circular chamber; a refractory wall within said chamber spaced from the outer wall thereof; a resistor at the bottom of said chamber disposed in the annular space between such walls; a series of electrodes depending vertically from above into such space to within arcing range of said resistor; a vertically adjustable frame over said chamber; conductors for supplying current to said electrodes, respectively, said conductors including sections secured to points on said frame spaced a predetermined distance apart; a pulley mounted in said frame adjacent each such conductor section; a cable adjustably connected with the corresponding electrode and passing over such pulley, said cable being counter-

8
weighted so as to tend to raise said electrode; and a cord connecting each pulley with the adjacent conductor section whereby the shortening of the latter tends to lower said electrode.

19. In an electric furnace of the character described, the combination with a resistor and a series of electrodes movable towards and away therefrom; of conductors for supplying current to said electrodes, respectively, said conductors including sections secured to points a predetermined distance apart; and means adapted automatically to move said electrodes individually, said means being affected by variations in length of the corresponding conductor sections due to changes in current flow therethrough.

20. In an electric furnace of the character described, the combination with a resistor and a series of electrodes movable towards and away therefrom; of conductors for supplying current to said electrodes, respectively, said conductors including sections secured to points a predetermined distance apart; means connected with individual electrodes tending to move the same away from said resistor; and connections between said means and the corresponding conductor sections, whereby variations in length of the latter serve to control said means.

Signed by me this 4th day of November, 1922.

CHARLES A. CADWELL.
